UNITED STATES PATENT OFFICE.

MYRON B. HAMMOND, OF BRIDGEPORT, CONNECTICUT.

DESIGN FOR A GARTER.

56,969.

Specification for Design.

Patented Jan. 25, 1921.

Application filed August 11, 1920. Serial No. 402,910. Term of patent 7 years.

To all whom it may concern:

Be it known that I, MYRON B. HAMMOND, a citizen of the United States, residing at the city of Bridgeport, in the county of Fairfield and State of Connecticut, have invented a new, original, and ornamental Design for a Garter, of which the following is a specification, reference being had to the accompanying drawing, forming part thereof, which is a view of the garter in elevation showing my new design.

I claim:

The ornamental design for a garter, as shown.

MYRON B. HAMMOND.
